UNITED STATES PATENT OFFICE.

ALFRED LADNER, OF PHILADELPHIA, PENNSYLVANIA.

DESIGN FOR A WATCH-CHAIN.

SPECIFICATION forming part of Design No. 21,109, dated October 13, 1891.

Application filed September 10, 1891. Serial No. 405,327. Term of patent 7 years.

To all whom it may concern:

Be it known that I, ALFRED LADNER, a citizen of the Republic of France, and a resident of Philadelphia, Pennsylvania, have invented 5 a Design for a Watch-Chain, of which the following is a specification.

My design for a watch-chain is fully illustrated in the accompanying drawing, the main feature of my design being the representation, 10 in miniature, of a number of the tools used by machinists in their trades, interspersed with emblems of the trade, as fully shown in said drawing, which represents the chain extended.

15 The bar *a* of the chain is represented as a miniature S-wrench. This bar is connected to the emblem *b*, representing a steam-governor, which in turn is connected to a miniature pair of outside calipers *c*, the arms *c'* of

these calipers being connected by two chains 20 to a representation *d* of a gear-wheel, and this representation of a gear-wheel is in turn connected to the legs of a pair of inside calipers *e*, which are connected to a square *f*. *g* is the miniature representation of a hammer connected at one end to the square and at the opposite end to the snap *h*. 25

I claim—

The design for a watch-chain, as herein shown and described. 30

In testimony whereof I have signed my name to this specification in the presence of two subscribing witnesses.

ALFRED LADNER.
